[57] CLAIM

The ornamental design for a cassette head cleaner, as
shown and described.

DESCRIPTION

FIG. 1 is a front elevational view of a cassette head
cleaner showing my new design;

FIG. 2 is a top plan view thereof;

FIG. 3 is a rear elevational view thereof;

FIG. 4 is a side elevational view thereof, the opposite

side being a mirror image;

FIG. 5 is a bottom plan view thereof.
